UNITED STATES PATENT OFFICE.

JOHN TROWBRIDGE, OF CAMBRIDGE, MASSACHUSETTS.

TELEPHONE.

SPECIFICATION forming part of Letters Patent No. 756,437, dated April 5, 1904.

Application filed May 18, 1903. Serial No. 157,561. (No model.)

To all whom it may concern:

Be it known that I, JOHN TROWBRIDGE, a citizen of the United States, and a resident of Cambridge, in the county of Middlesex and State 5 of Massachusetts, have invented new and useful Improvements in Telephones, of which the following is a specification.

The object of my invention is to relay or repeat telephonic current undulations in such 10 manner that relatively feeble undulations in one telephone line will be reproduced in another line with enhanced force and amplitude and without impairment of the essential telephonic character of the current undulations 15 and consequent deterioration of articulation and to provide such a relay apparatus that the telephonic system as a whole, including relays, will reciprocate—that is to say, will transmit speech-messages electrically in either 20 direction, as in the case of the ordinary continuous line.

In United States Letters Patent to Samuel Sheldon and myself, No. 407,799, dated July 30, 1889, there is described a device whereof 25 the purpose was to utilize powerful electrodynamic currents to energize magnets in a relay apparatus. This apparatus was also intended for use as a receiving instrument. As the continuous current generated by a dynamo 30 involves the employment of a commutator, there is set up in the current a rapidly-recurring series of pulsations or throbs due to the action of the commutator, and, as was pointed out in the said Patent No. 407,799, the inductive pulsations produced by the commutator 35 wherever an armature-coil is employed which intersects the lines of force of the surrounding magnetic field (such as is illustrated by Siemens's Patent No. 149,797, dated April 14, 1874) will, if the armature be employed as part of a telephonic system, overpower the 40 more delicate undulations characteristic of a telephonic current. Consequently, as the specification of the Trowbridge and Sheldon 45 Patent No. 407,799 sets forth in detail, the object was to arrange an armature wound and suspended in the field of a dynamo-current-excited electromagnet in such manner as to 50 elude the disturbing commutator influences, and thus be capable of transmitting speech as

a relay or as a receiver. Unfortunately for the practical accomplishment of this purpose, the hypothesis of the said Patent No. 407,799 failed to take account of other factors, both electromagnetic and mechanical, and consequently 55. the apparatus as a whole, although it obviated the difficulties due to commutator disturbances, failed satisfactorily to transmit the electrical undulations characteristic of and essential to the production of articulate-speech 60 sounds. The net failure of the said apparatus may be correctly characterized thus: The instrument of Patent No. 407,799, whether used as a relay or as a receiver, was incapable of transmitting through its several transforming 65 members, unimpaired and constant in character, the telephonic undulations of the incoming line. The undulations emitted by the instrument were more or less confused with disturbing undulations superposed upon the 70 correctly-modulated incoming waves or pulsations, so that when finally transformed into sound-waves they lost, in whole or in part, the essential quality of articulate speech. This 75 imperfection was usually manifested by confused buzzing or rattling sounds, which always interfered with and often destroyed the pure essential articulate-speech sounds. The Patent No. 407,799, however, set forth a mode 80 of enhancing or amplifying the feeble undulations of a nearly-exhausted telephonic current by converting the undulations thereof into magnetic undulations within a supplemental magnetic field, although, as I have pointed out and as experience proved, the mode of accomplishing this result shown in the said patent 85 failed to take account of many then unsuspected conditions, and thus failed to produce the useful result of transmitting and forwarding with unimpaired articulation the undulations 90 of the incoming current.

I have discovered the electrical and mechanical causes of the defects of the instruments described in Patent No. 407,799 and have by my present invention herein set forth provided 95 an apparatus which by the aid of a symmetrical or balanced magnetic field amplifies the feeble undulations of a nearly-exhausted telephone-line and repeats or transmits them unimpaired in articulate quality to 100

a second line, thus preserving the exact undulatory correspondence with the sound-waves of articulate speech.

My invention consists of a novel method of 5 repeating electrical undulations and also of an apparatus which employs my new method to transmit and repeat telephonic messages. In an application for United States Letters Patent, Serial No. 157,560, filed concurrently 10 herewith I have set forth and claimed my said method, and I therefore wish it to be understood that while this specification for the purpose of explanation involves a description of my method I reserve the same in whole 15 and part for claim in the said concurrent application.

In the drawings hereto annexed, Figure 1 is a plan view, partly diagrammatic and conventional, of a telephonic repeating instrument or relay embodying my invention. Fig. 2 is a diagram of a complete telephone-line with a single reciprocating relay-station. Fig. 3 is a diagram of a non-reciprocating telephone-line with two relays arranged tandem. Fig. 4 is a diagram of a reciprocating tandem relay-line, and Figs. 5 and 6 show other forms of repeating instruments or relays.

Referring to Fig. 1, upon a suitable base and by means of brackets $M' M'$ are mounted 30 a pair of horseshoe-magnets $M M$. These may be permanent magnets or electromagnets. In the latter case they should be energized by a continuous and steady current, as from a primary or storage battery. Likewise mounted 35 on the base is a telephonic transmitter T , which is here shown as a "solid-back" carbon-button transmitter. Firmly and rigidly mounted on the impulse-receiving member of the transmitter T , as by a stem P , there is an 40 armature A , which is preferably composed of soft-iron rods or short wires. At the ends of the armature A are secured transverse pole-pieces $a a$, likewise of soft iron. I have found by experiment that these pole-pieces while not 45 essential to the performance of my invention nevertheless increase the responsive delicacy of the instrument. The magnets $M M$ are arranged with their north and south poles $N S$ mutually opposite each other, or, in other 50 words, the north poles of the magnets $M M$ are diagonally opposite, as also are the south poles. The resulting induced polarity of the armature pole-pieces $a a$ is as shown in Fig. 1 by the letters $n s$. Adjusting-screws M^2 enable 55 the operator to adjust the magnet-poles $N S$ as close as desired to the armature pole-pieces. These screws should be of brass or other diamagnetic material. The magnets $M M$ should be of equal strength, so as to maintain 60 substantial equilibrium in the field and with respect to the armature A .

The mode of mounting the magnets $M M$ in polar opposition, as shown, establishes a field which may be described as quadrilateral 65 and symmetrical or balanced, and the arma-

ture A is normally in a state of equilibrium, the balanced forces of the magnetic field exerting no stress upon the impulse-receiving member of the transmitter T . This condition I regard as important, because the transmitter T , whatever be its specific character, is thus maintained in precisely the same delicately-responsive state that characterizes a transmitter which is prepared in the usual and proper way for the reception of sound-waves. 70 I have found by careful experiment that with an armature in an unbalanced non-symmetrical magnetic field connected directly to a transmitter—say to a diaphragm—the constant pull of the magnetic field causes a distortion of the diaphragm, and consequently produces disturbing effects which obscure the proper articulation of the instrument. 75

The incoming telephonic line L we will suppose to be at such a distance from the transmitting devies at its remote end that the electrical undulations are feeble, so that reproduction of audible speech thereby in the usual manner is impracticable. In circuit with the line L , I wind an armature-coil l' on the armature A , preferably bunching the coil in two parts near the ends of the armature, leaving the middle portion thereof bare of coil, and thus obtaining practically all the electromagnetic effect of the coils l' while saving 95 weight.

The transmitter T is wired in the usual manner, a battery B of proper strength in its immediate circuit. In this circuit is also located the primary of an induction-coil I , whereof the secondary is in the outgoing or relay line R . 100

When the incoming line L is quiet and no electrical undulations are passing on it, the relay instrument is in equilibrium; but when 105 electrical undulations are set up in this line the polarity of the armature A is varied in exact correspondence and consonance with the electrical undulations in the line L , and an undulating or vibrating magnetic field is generated in the field of the magnets M . The resulting effect is the product of the armature-coil effects and the balanced-field effect, and the magnetic, and consequently the mechanical, results are enhanced and amplified. 110 Within quite generous limits the strength of the balanced magnetic field may be raised and the consequent product effects increased. Moreover, by means of the polar relationship 115 of the field and armature coil all torsional moments are in equilibrium and the resultant mechanical vibrations are in a straight line and are exerted in this straight line perpendicularly to the impulse-receiving member 120 of the transmitter T and perpendicularly to the planes of contact between the resistance-varying members of the transmitter. This same rectilinear transmission of mechanical effects and perpendicular impact may readily 125 be secured whatever be the structural char- 130

acter of the transmitter. By preserving these conditions the relay or repeating instrument sends to the outgoing or relay line R undulations precisely corresponding to the incoming 5 undulations of the line L, which excite the armature-coil i' and bring into action the vibration-amplifying forces of the balanced field of the magnets M. Thus the transmitter T is impressed with amplified undulating 10 impulses, which are essentially the same in articulate character as the sound-waves which excited the sending instrument at the remote end of the line L, and consequently transmits to the line R unimpaired in articulate quality 15 amplified undistorted undulations essential to the production of intelligible articulate speech, which may then be made manifest by a proper telephonic receiver at the remote end of the line R.

20 The relay or amplifying effect sensible at the receiver end of the line R is due to several conditions—first, the product magnetic amplifications of the armature-coil undulations by means of the balanced magnetic field, 25 whereby the mechanical impress upon the transmitter T is emphasized; second, to the relay-battery B, which supplies fresh electrical energy for transmission of undulations along the line R, and, third, to the preservation 30 and transmission, unimpaired and unobscured and undistorted by extraneous influences, of the undulatory articulations of the original telephonic current.

In Fig. 2 there is illustrated by diagram an 35 arrangement for obtaining reciprocal relay effects between two distant stations. At one station is located the usual transmitter T', with battery B' and the primary of the induction-coil I' in its circuit. The line L', including 40 the secondary of the induction-coil I', armature-coil at A, the secondary of the induction-coil i , and the receiver R', leads to the relay-station. At this relay-station two instruments similar to that shown in Fig. 1 and 45 above described are set up, the instrument M M A T in adjustment to receive and repeat impulses from transmitter T' and the instrument $m m a t$ to receive and repeat impulses from transmitter T², which is at the end of the 50 line remote from transmitter T'. The two relay instruments at the relay-station are arranged as follows: The same circuit R includes the two transmitters T_t, the relay-battery B, and the primaries of the induction-coil I and i . At the station remote from the 55 instruments T' and R' are located the transmitter T², with the battery B² and the primary of the induction-coil I² in circuit. The line L² includes the secondary of the induction-coil I², the receiver R², armature-coil a , and the secondary of induction-coil I. The operation 60 of this system is as follows:

Speech vibrations stimulate current undulations in the primary of coil I' and generate 65 corresponding undulations in the line L'.

These electrical undulations are converted into magnetic undulations at the armature-coil A, and these again are supplemented by reciprocal magnetic effects of the balanced field of magnets M M. As above described 70 in connection with Fig. 1, these reinforced magnetic undulations are reconverted into electrical undulations precisely corresponding to the original speech vibrations at the transmitter T', and these undulations in circuit R set 75 up corresponding undulations in the circuit L², which are in the usual manner finally reconverted into sound-waves at the receiver R², where the speech delivered at transmitter T' is reproduced. 80

The current undulations of the circuit L' passing through the secondary of the coil i produce in its primary no sensible effect. Thus the resistance to the transmission of undulatory effects backward, as we may say, through 85 the relay instrument $m m a t$ is practically prohibitory.

When the speech is made at transmitter T², the reciprocal effect is perfect. The relay $m m a t$ receives, amplifies, and transmits the undulations to the line L' through the induction-coil i , and the receiver R' reconverts them 90 into speech. Whatever be the source of undulations, the effective relay instrument takes the message and repeats it, one relay works 95 in one direction and the other in the opposite direction, and each automatically to the exclusion of the other. The practical results, therefore, which appeal to the users of the instruments at the ends of the line are the 100 same as if they were conversing over a simple telephone-line short enough to render the direct communicating undulatory current effective.

The preservation of the exact articulate 105 character of the undulatory current which is peculiar to my method of repeating enables one to use several relays like that shown in Fig. 1 or relay-stations like that shown in Fig. 2 in tandem. I illustrate a simple non-reciprocating tandem relay-line in Fig. 3. Therein the impulses from transmitter T' excites the relay at station 1, thence the undulatory current is passed on amplified to station 2, and thence to receiver R². 110 115

In Fig. 4 I illustrate an arrangement of complete reciprocating relay-stations in tandem. In this system the arrangement of terminal station T' R' with relation to relay-station 1 and that of terminal station T² R² with 120 relation to relay-station 2 are the same as the relations of the respective terminal stations of Fig. 2 of the relay system. The secondary of the induction-coil I, the armature-coil of relay instrument 2^a, the secondary of induction-coil i^2 , and the armature-coil of relay instrument 1^b are in the line which stretches 125 between relay-stations 1 and 2. I have constructed a system of this character in which the line-resistances were analogous to a line 130

from New York to Chicago as between terminal T' R' and relay-station 1, a line from Chicago to Omaha as between relay-stations 1 and 2, and a line from Omaha to Denver as between relay-station 2 and terminal station T² R², and have maintained clear, audible, and unimpaired a conversation with an assistant over the said line, which transmitted speech reciprocally as readily as an ordinary short 10 telephone-line.

It will be observed that in contrast with the instrument and mode of operation described in Patent No. 407,799 I have by my present invention produced the following electrical, magnetic, and mechanical conditions: Instead of converting the product effects of an armature and surrounding field into rotary movements by means of unbalanced torsional magnetic product effects characteristic of the 15 said patent I have maintained torsional balance in magnetic effects and produced direct rectilinear mechanical movements. Whereas in the instrument of Patent No. 407,799 the curvilinear mechanical impulses of the suspended armature caused distortions and disturbances in the transmitter, in my present invention no such distortion or disturbances take place. Instead of making contact between the armature-coil and the receiving 20 members of a transmitter by means of initial pressure (itself a cause of mechanical distortion and confusion of articulate with inarticulate electrical undulations) I have secured the armature-coil directly and rigidly to the receiving member of the transmitter, thus avoiding 25 any confusing stresses and also eliminating the effect of individual non-electric vibrations of the independently-suspended armature. In short, I have by my present invention contrived a method and apparatus whereby a symmetrical or balanced magnetic field, as an independent source of power, is enabled 30 in coaction with an exciting-armature to repeat unimpaired the articulate undulations of a telephonic circuit with fresh and amplified 35 transmission impulses in a second or relay circuit, whereas by the apparatus and mode of operation shown in Patent No. 407,799 this functional result could not be obtained. Also 40 I have by my present invention contrived a method and apparatus whereby the symmetrical or balanced magnetic field in connection with an exciting-armature may be employed 45 to directly produce the mechanical vibrations 50 of a receiver-diaphragm, so that the resulting sounds will be clear undistorted articulate 55 speech free from disturbing sounds.

In solid-back microphone-transmitters now in general use the metallic diaphragm D is, as 60 shown in Fig. 5, rigidly clamped at its edges to a casing, on which the electrode-holder is also rigidly fixed. The stem P is fixed rigidly at one end to the middle of the metallic dia- 65 phragm and at its opposite end to the middle

of the usual mica diaphragm closing the end 65 of the electrode-holder and against which the movable electrode of the microphone bears. This is the usual construction, and in carrying my invention into effect the only change necessary to make in the microphone-trans- 70 mittor as at present constructed is to mount the small iron armature A on the stem P between the metallic and mica diaphragms and fix the two magnets M within the casing of the transmitter properly disposed with relation 75 to the iron armature A.

In Fig. 6 I have shown another form of instrument, which differs from that above described in that a block D' of whitewood is fixed to the middle of the metal diaphragm, 80 and in this block D' the armature A is mounted with only its two ends projecting therefrom. By thus practically burying the armature in the block of wood D independent vibrations 85 of said armature, which might conflict with the vibrations consonant with the electrical undulations, are prevented, the inclosing body of wood tending to smother the same without itself being vibrated.

In telephone systems comprising a plurality 90 of repeating instruments I find that it is desirable to make each adjustable—that is, to provide some means by which the action of each instrument may be regulated so as to work in harmony with the other instruments of the 95 system. To this end I may provide each instrument with a spring-finger d, fixed to any suitable support and arranged to press through a block of rubber d² upon the side of the block D'. The pressure of the spring-finger d may 100 be regulated by means of a screw d¹, by means of which the action of the instrument may be regulated to accord with the other instruments of the system. The arrangement shown in 105 Fig. 5 has the advantage of supporting the vibrating armature A at both sides, so that the slight bending effect due to the weight of the armature is wholly obviated. Any support at the side away from the transmitter T will 110 serve for this purpose; but I prefer to employ a diaphragm clamped at its periphery for two reasons. First, the diaphragm does not 115 tend to confuse the pure articulate vibrations of the armature by independent tremors of its own, and, moreover, the diaphragm itself 120 used in the manner described produces audible speech, which enables the listening operator to detect any disturbing influences which may be at work, and thus to ascertain if the instrument is working properly to relay the 125 message. A damping device, such as indicated in Fig. 6, may be thus employed to suppress any undesirable vibrations.

With a single relay-station in line the disturbing effects due to local vibration in my 125 relay instruments are so slight as to be negligible; but with a tandem arrangement employing several relay-stations the local dis-

turbances negligible with a single station are liable to accumulate at each relay and should be suppressed.

What I claim is—

- 5 1. In an instrument for repeating electrical undulations, the combination of a magnetic field, an armature-coil in a position of balance therein, a telephonic transmitter, and connections arranged with relation to the reciprocal effects of the coil and magnetic field to impart mechanical vibrations perpendicularly to the receiving member of the transmitter.
- 10 2. In an instrument for repeating electrical undulations, the combination of a magnetic field, an armature-coil in a position of balance therein, a telephonic transmitter outside the balanced field, and connections arranged with relation to the reciprocal effects of the coil and magnetic field to impart mechanical vibrations perpendicularly to the receiving member of the transmitter.
- 15 3. In an instrument for repeating electrical undulations, the combination of a magnetic field, an armature-coil in a position of balance therein, a telephone-transmitter, and connections arranged with relation to the reciprocal effects of the coil and magnetic field to impart mechanical vibrations to the receiving member of the transmitter in a straight line.
- 20 4. In an instrument for repeating electrical undulations, the combination of a magnetic field, an armature-coil in a position of balance therein wound so that the mechanical vibrations due to the reciprocal magnetic effects of the coil and field are rectilinear, a telephonic transmitter, and connections to impart thereto the said rectilinear mechanical vibrations.
- 25 5. In an instrument for repeating electrical undulations, the combination of a magnetic field, an armature-coil in a neutral location in the field, a telephonic transmitter, and connections arranged with relation to the reciprocal effects of the coil and magnetic field to impart mechanical vibrations perpendicularly to the receiving member of the transmitter.
- 30 6. In an instrument for repeating electrical undulations, the combination of a magnetic field, an armature-coil in a neutral location in the field wound so that the mechanical vibrations due to the reciprocal magnetic effects of the coil and field are rectilinear, a telephonic transmitter, and connections to impart thereto the said rectilinear mechanical vibrations.
- 35 7. In an instrument for repeating electrical undulations, the combination of a magnetic field, an armature-coil in a position of balance therein, a telephonic transmitter, and a stem rigidly connecting the armature-coil with the receiving member of the transmitter.
- 40 8. In an instrument for repeating electrical undulations, the combination of a magnetic field, an armature-coil in a neutral location in the field, a telephonic transmitter and a stem rigidly connecting the armature-coil with the receiving member of the transmitter.

9. In an instrument for repeating electrical undulations, the combination of a magnetic field, an armature-coil in a position of balance therein, a transmitter, a stem fixed to the transmitter's receiving member and to the armature-coil, the coil, stem and transmitter arranged with relation to the reciprocal magnetic effects of the coil and field to impart rectilinear mechanical vibrations to the receiving member of the transmitter. 70

10. In an instrument for repeating electrical undulations, the combination of a magnetic field, an armature-coil therein, a telephonic transmitter, a mounting for the armature secured to the transmitter at one side and on a support at the other side. 80

11. In an instrument for repeating electrical undulations, the combination of a magnetic field, an armature-coil therein, a telephone-transmitter at one side of the armature, a diaphragm at the other, and a mounting for the armature secured at one end to the transmitter and at the other to the diaphragm. 85

12. In an instrument for repeating electrical undulations, the combination of a pair of horseshoe-magnets arranged with their similar poles in diagonal opposition, an armature-coil in neutral location in the field of the said magnets, a transmitter, connections between the transmitter and armature-coil, the coil wound with relation to the field to impart rectilinear vibrations to the transmitter. 90

13. In an instrument for repeating electrical undulations, the combination of a pair of horseshoe-magnets arranged with their similar poles in diagonal opposition, an armature-coil in neutral location in the field of the said magnets, a transmitter on one side of the coil and a support on the other, and a stem holding the armature, and connected with the transmitter 100 and the support. 105

14. In an instrument for repeating electrical undulations, the combination of a pair of horseshoe-magnets arranged with their similar poles in diagonal opposition, an armature-coil in neutral location in the field of the said magnets, a transmitter on one side of the coil and a diaphragm on the other and a stem holding the armature, secured to the transmitter and to the diaphragm. 110

15. In a telephone system, two telephone-lines, a pair of relay instruments whereof the principal parts are a microphonic transmitter, an armature-coil connected to the transmitter, and a magnetic field surrounding the armature-coil, each of the two telephone-lines branched to include the armature-coil of one relay in one branch and the transmitter of that relay in the other branch inductively. 115

16. In a telephone system, in combination, a battery-circuit, a battery therein; two induction-coils, each having its primary arranged in said circuit, two transmitters in said circuit, two magnetic fields one for each transmitter; two armature-coils one in each field 125 130

and each controlling the transmitter of its respective field; two telephone-circuits each including one of said armature-coils and also the secondary of one of the induction-coils.

- 5 17. In a telephone system, in combination, a battery-circuit; a battery therein; two induction-coils each having its primary arranged in said circuit; two transmitters in said circuit; two magnetic fields one for each transmitter; 10 two normally balanced armature-coils one in each field and each of said coils arranged to control one of the transmitters and two telephone-circuits each including one of said armature-coils and also the secondary of one of the induction-coils.

15 18. In a telephone system in combination, a battery-circuit; a battery therein; two in-

duction-coils each having its primary arranged in said circuit; two transmitters in said circuit; two magnetic fields one for each transmitter; 20 two normally balanced armatures, one in each field each of said armatures being provided with an armature-coil and arranged to control one of the transmitters, and two telephone-circuits each including one of said armature-coils and also the secondary of one of the induction-coils.

Signed by me, at Boston, Suffolk county, Massachusetts, this 5th day of May, 1903.

JOHN TROWBRIDGE.
